CLOSURE FOR DRY POWDER DISPENSING CANS

Odell Wilson, Rocky River, Ohio, assignor to Corega Chemical Company, Cleveland, Ohio, a corporation of Ohio

Application November 2, 1931. Serial No. 572,464

2 Claims. (Cl. 221—61)

This invention relates to a cover or cap for a dispensing can.

Dispensing cans are widely used as containers for powdered substances. As ordinarily constructed, the can has a body which may be of any desired size or shape and which is adapted to hold a suitable quantity of the powdered substance, while the top of the can is fitted with a neck or spout having a sifter top through which the contents of the can may be discharged.

It is customary to provide a cover or cap which fits over the top of the neck or spout to prevent spilling of the contents in case the can is accidentally turned over, and this invention relates to such a cover or cap.

A cap for this purpose should fit the top of the can snugly so as to close the holes in the top, and must be easily removed and replaced. It must be secured in place rigidly enough that it will not come off except when intentionally removed. The cap should present an attractive appearance, and since cans of this kind are ordinarily thrown away when empty, it is essential that the cap be inexpensive to manufacture.

It has been found impractical to construct the cap and the neck of the can to such limits of accuracy that they will always match with exactly the proper frictional engagement. The result is, that the caps sometimes fit very tightly and it is a difficult task to remove them, especially since a cap of this kind is usually of small size and difficult to grasp.

When the cap is removed, it is usually given a slight twist in addition to being pulled directly away from the end of the top of the can. The caps which have been produced heretofore have had a relatively small knurled or fluted surface on which the fingers were apt to slip when the cap was removed.

It is one of the objects of the present invention to provide a cap having a large fluted or knurled portion which will prevent the fingers slipping when the cap is removed.

Other objects of the invention and features of novelty will be apparent from the following description taken in conjunction with the accompanying drawing, of which:

Fig. 1 is a side view of a dispensing can fitted with a cap embodying my invention, the cap and parts of the neck of the can being broken away and shown in section.

Fig. 2 is a side view of a cap embodying my invention, certain parts of the cap being broken away and shown in section, and

Fig. 3 is a top view of the cap shown in Figs. 1 and 2.

Referring to the drawing, 10 indicates generally the body of a dispensing can, which may be of any desired size and shape. The can as shown is made of thin sheet metal and has a top section 11 to which the neck 12 is attached. A small flange 13 is formed on the neck 12 where it joins the can. The neck 12 is a short cylindrical sheet metal member having a slightly convex top portion 14 in which are placed a plurality of holes 15 through which the contents of the can are discharged.

The cap provided by my invention is a small cup-shaped sheet metal member and is intended to fit over the neck so as to be held by frictional engagement.

The cap, which is indicated generally by the numeral 16, has an annular enlargement or skirt 17 at its open end, so that the cap will fit down over the flange 13 at the base of the neck 12. This enlargement or skirt also aids in placing the cap on the neck, as it is somewhat larger than the neck and helps to center the cap on the neck. Immediately above the portion 17 is a somewhat smaller section 18 which is proportioned so as to fit snugly around the neck 12 and hold the cap in place by frictional engagement. The portion 18 is made of sufficient width to permit the ends of the fingers to extend into this portion when the cap is removed.

Above the portion 18 is a wide annular enlarged portion 19 which is suitably knurled or fluted, as at 20, to provide a gripping area for the fingers. The cap is proportioned so that the portion 19 extends above the upper extremity of the neck. This permits the fluted portion 19 to be made wider than would otherwise be possible with a neck of equal height.

The imperforate top 21 of the cap is depressed below the top of the fluted or knurled portion 19, leaving an annular ring 22 around the outside of the top. The central portion of the top 21 is made slightly convex to fit the convex top on the neck of the can. It will be seen that the cap is constructed so that a line tangent to the center of the curved central portion of the cap will be below the upper end of the fluted portion 19. This construction permits the top of the cap to rest against the top of the neck so as to prevent loss of the contents of the can.

Furthermore the upper part of the skirt portion extends above the place where the curved plane of the top portion of the cap would in-

tersect the skirt portion if the curved plane were extended.

It will be seen that the cap constructed in accordance with my invention has a wide fluted portion which extends above the closed end and which includes the annular portion surrounding the depressed end. This construction permits the fluted area to be made much wider than is otherwise possible. The large fluted area furnishes ample gripping surface for the fingers so they will not slip when the cap is being removed.

If desired, a disc made of any suitable material, such as felt, may be placed inside the cap so that this disc will bear against the top and close the sifter holes.

When the cap is pushed down on the neck, the top 21 of the cap fits snugly against the top 14 of the neck so as to close the holes 15 and prevent loss of the contents of the can.

The cap provided by my invention is easily removed as it has a large knurled or fluted portion which the fingers can grip so that the cap can be turned or pulled off, while there is a depressed portion into which the ends of the fingers can project so that they can more effectively grip the knurled or fluted portion. The large gripping area which is provided on this cap makes it an easy matter to remove the cap even when it is tightly secured on the neck. The cap is easily replaced as the enlarged portion adjacent the open end helps to align the cap on the neck, so that it is then only necessary to push the cap down on the neck.

35.

In addition, the cap provided by my invention is of simple construction, is inexpensive to manufacture, and has an attractive appearance.

Having thus described my invention, I claim:

1. The combination with a container having an upstanding portion with a convex curved perforated top, a removable cap having a skirt portion which frictionally engages the upstanding portion, the top of the cap being curved to fit against the curved top of the upstanding portion, the upper portion of the skirt of the cap extending above the place where the projected arc of the curved top portion of the cap would intersect the said skirt portion to thereby provide an extended finger gripping portion for removal of said cap.

2. The combination with a container having an upstanding portion with a convex curved top of continuous surface except for several relatively small perforations, a removable cap having a skirt portion adapted to engage the aforesaid upstanding portion to thereby retain the cap upon the upstanding portion, the top portion of the cap being imperforate and adapted to engage the top surface of the aforesaid upstanding portion substantially throughout the extent thereof, the upper portion of the said skirt of the cap extending above the place where the projected top portion of the cap would intersect the said skirt portion, thereby providing an extended finger gripping portion for removal of said cap.
